P. W. JONES

CLASP

Filed Dec. 6, 1927

INVENTOR.
Percival W. Jones.
BY Barlow & Barlow
ATTORNEYS.

UNITED STATES PATENT OFFICE.

PERCIVAL W. JONES, OF PAWTUXET, RHODE ISLAND, ASSIGNEE TO ROSENHEIM CO. INC., OF PROVIDENCE, RHODE ISLAND, A CORPORATION OF RHODE ISLAND.

CLASP.

Application filed December 6, 1927. Serial No. 238,071.

This invention relates to an improved construction of clasp for chains such as flexible bracelets and the like; and has for its object to provide a locking member to prevent accidental disengagement of the clasp.

A further object of the invention is to slidably mount a locking member on one of the terminal links of the chain to be moved into a position to block a disengaging movement of the fingerpiece of the clasp.

A still further object of the invention is to provide such a lock which will be neat in appearance and not detract from the ornamental effect of a bracelet which is worn for personal adornment.

With these and other objects in view, the invention consists of certain novel features of construction, as will be more fully described, and particularly pointed out in the appended claims.

In the accompanying drawings:

Figure 1 is a perspective view of a portion of a chain made up of a plurality of links with the locking member for the clasp in locking position.

Figure 2 is a perspective view of one of the terminal links of the chain.

Figure 3 is a perspective view of the locking member.

Figure 4 is a perspective view of the terminal link and the locking member mounted thereon.

Figure 5 is a perspective view of the latch.

Figure 6 is a perspective view of the opposite terminal link of the chain with the latch pivotally mounted thereon.

Figure 7 is a sectional view on line 7—7 of Figure 4.

Figure 8 is a sectional view taken on line 8—8 of Figure 4.

Figure 9 is a sectional view of the terminal links of the chain with the locking member for the clasp in withdrawn position.

Figure 10 is a similar view with the locking slide member in its locking or working position.

Figure 11 is a view taken on line 11—11 of Figure 10 looking in the direction of the arrow.

The clasp illustrated while adapted for use to connect any terminal links of a bracelet, chain or the like, is designed more particularly for use as a so-called center catch to be

used in connection with a wrist watch bracelet to permit the center of the bracelet to be detached for removing the watch and bracelet from the wrist rather than unhooking portions of the bracelet which engage the bails of the wrist watch and to prevent accidental depression of the detaching fingerpiece and loss of the bracelet and wrist watch, it is found desirable to provide a locking member to prevent operation of the fingerpiece; and the following is a detailed description of the present embodiment of this invention showing one means by which such advantageous locking device may be formed:

With reference to the drawings, 10 designates a link bracelet, 11 one terminal link and 12 another terminal link thereof. The link 12 is provided with a compressible latch 13 pivoted thereto by means of a pin 14. This compressible latch has portions 15 to engage abutments 16 carried by the terminal link 11 as clearly illustrated in Figures 9 and 10, to prevent detachment of the links 11 and 12. A fingerpiece 17 is formed integral with the latch 13 by extending a portion of the stock upwardly therefrom and folding the same back upon itself, which fingerpiece may be pushed inwardly to release the latch from the abutments 16 and permit detachment of the terminal links 11 and 12.

In order to lock the latch against disengagement, the fingerpiece is undercut as at 18 and a locking member 19 is mounted on the link 11 with extending arms 20 to be moved into the undercuts 18 of the fingerpiece to block the depression thereof. This locking member is provided with wing portions 21 which extend through slots 22 in the terminal link 11 and are folded loosely beneath the wall 23 of this link to securely mount the locking member against accidental detachment and yet allow a sliding movement thereof.

A handle portion 24 is raised from the stock of the locking member to permit of easy manipulation thereof and a detent 25 is also formed to extend into the recess 26 in the top wall 23 to secure the locking member in set position with portions beneath the fingerpiece 17. The stock of the locking slide is sufficiently resilient and the detent 25 sufficiently rounded or ball shape to permit the detent to be raised out of the recesses 26 by sufficient pressure on the handle portion 24

and this resiliency also tends to force the detent and recess parts together to hold them in firm frictional engagement.

It will be apparent that the lock which I have described is of simple, and practical construction and one which may be advantageously employed upon an ornamental series of links for bracelets or the like.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a chain, terminal links, a compressible latch carried by one terminal link, and an abutment carried by the other terminal link and engageable with the latch when non-compressed to hold the links together, a finger piece having overhanging portions movable to compress said latch, a member slidably mounted on one of said terminal links having 25 extending arms to be moved beneath said overhanging portion of said finger piece to block its movement to compress said latch.

2. In a chain, terminal links, a compressible latch carried by one terminal link, and an 30 abutment carried by another terminal link and engageable with the latch when non-compressed to hold the links together, a finger piece for operating said latch, a member bodily slidably mounted on the outer surface 35 of one of said terminal links to be moved along the outer surface and beneath said finger-piece to prevent it from operating said latch, and detent and recess means between said link and the end of said member for 40 retaining said member in set position on said link.

3. In a chain, terminal links each having 45 a top wall, a compressible latch carried by one terminal link, an abutment carried by another terminal link and engageable with the latch when non-compressed to hold the links together, a finger piece carried by said latch for compressing the same, a slot in the top wall of one of said terminal links, a 50 member having a portion extending thru said slot for bodily slidably mounting it on said

link, said member being movable to engage said finger piece to block it from being manipulated to compress said latch.

4. In a chain, terminal links each having 55 a top wall, a compressible latch carried by one terminal link, an abutment carried by another terminal link and engageable with the latch when non-compressed to hold the links together, a finger piece carried by said latch for compressing the same, slots in the top wall of one of said terminal links, a member having portions extending thru said slots and folded loosely beneath said wall for securing it thereto and for bodily slidably 60 mounting it on said link, said member being movable to engage said fingerpiece to block it from being manipulated to compress said latch.

5. In a chain, terminal links, a compressible latch carried by one terminal link, and an abutment carried by another terminal link and engageable with the latch when non-compressed to hold the links together, an integral substantially T-shaped finger piece extending from said latch for compressing the same, the terminal link carrying said abutment having longitudinally extending slots 75 therein, a member having portions extending into said slots and slidably mounted on said link, spaced extending arms on said member to extend under the T-shaped head of said finger piece to block a movement to compress said latch, a handle portion on said member to assist in sliding it to and from locking position, and detent and recess means between said member and the link upon which it is mounted to retain said member in locking position.

6. In a chain, terminal links, a compressible latch carried by one terminal link, an abutment carried by the other terminal link and engageable with the latch when non-compressed to hold the links together, a finger piece movable to compress said latch, and a 90 member bodily slidably mounted on the outer surface of one of said terminal links and having extending arms to be moved beneath said finger piece on opposite sides thereof to block its movement to compress said latch. 100

In testimony whereof I affix my signature,
PERCIVAL W. JONES.
